UNITED STATES PATENT OFFICE.

WILFRED ROTHERY WOOD, OF LONDON, ENGLAND.

MECHANICAL STOKER.

Application filed January 6, 1921. Serial No. 435,484.

To all whom it may concern:

Be it known that I, WILFRED ROTHERY Wood, a citizen of the United States of America, residing in London, England, have 5 invented certain new and useful Improvements in Mechanical Stokers, of which the following is a specification.

An endless travelling grate stoker is known in which the lower run of the grate 10 is contained in a trough in the front end of which there is sufficient water to form a seal preventing escape, at this end of the grate, of air which may leak from the boxes constructed under the upper run with the object 15 of supplying air at a pressure graduated from front to rear of the grate. The riddlings from the upper run of the grate fall to the bottoms of the boxes and have to be removed therefrom, while the said bottoms 20 prevent radiation from the upper run to the surface of the water.

The essential feature of the present invention consists in a water trough beneath the 25 endless grate the surface of the water in which is freely exposed to radiation from the upper run of the grate, while more or less of the length of the lower run travels beneath the surface of the water.

Several advantages accrue from this feature 30 of the invention.

It frequently happens that for one reason or another the endless grate is brought to rest while combustion remains vigorous on the upper run. In these circumstances there 35 has hitherto been a tendency for the metal of the upper run of the grate to become overheated and damaged. This is prevented by the invention, since the steam developed by the radiation received at the surface of the 40 water comes in contact with the metal of the upper run and cools it.

By providing a plate to act as a curtain extending from the under surface of the upper run to below the surface of the water in 45 the front part of the trough, there is formed a chamber beneath the grate which may receive air when the pressure beneath the upper run is to exceed that of the atmosphere and may be effectually sealed by the said 50 plate. Or, the curtain being adapted to be raised to any desired height above the surface of the water, or being provided with an adjustable opening, the admission of air to the chamber may be controlled when the 55 draught is by suction through the grate instead of by pressure. Thus an actual box

construction beneath the grate is avoided, and there is the advantage that the bottom of the chamber is water, so that riddlings are not only immediately quenched, but are 60 automatically removed more or less completely by falling on to the lower run which carries them forward to be scraped off at the front of the grate, while that portion which falls through the grate to the bottom 65 of the trough may be removed by hand or otherwise. In the closed box construction previously used the riddlings were apt to burn in the box, overheating the several parts of the construction and leading to loss 70 of matter still available as fuel.

The foregoing advantage is even more marked when the system of graduated draught is adopted, since the collection of riddlings in the several compartments into 75 which the box construction was subdivided was even more troublesome than in an undivided box. By this invention the separate compartments are formed by successive curtains extending from the underside of the 80 upper run to the water surface and suitably adjustable or having suitably adjustable openings.

There is yet another very considerable advantage, namely that the trough may be 85 constructed of concrete or masonry and serve as the compression member of the whole construction. Hitherto much of the cost of the construction has resided in the iron compression members introduced in 90 compensation for the tension exerted by the endless grate. Such members could not well be avoided while they had also to fulfil the function of carrying the box construction 95 aforesaid.

The accompanying drawing shows a diagrammatic longitudinal section through a traveling grate stoker having the improvements according to the invention.

The endless grate runs over the front and rear rollers *b* and *c* respectively and is driven in the known manner. The object of the particular longitudinal curvature of the upper run has been described in the specification to my application for United States Letters Patent Serial No. 435,483 of even date herewith and forms no part of this invention. At the rear end of the upper run is a grate platform or stage *g* from which the clinker and ashes are discharged. The lower run travels in the water contained in the trough *d* of concrete, the sides of which 100 105 110 115

carry plates *e* forming the sides of the chamber beneath the upper run of the grate. The latter is supported on rollers *f* journalled in the upper parts of plates *e*.

5 The roller *b* is carried in bearing blocks mounted on the sides of trough *d*, one such block being shown at *b'*. The block is mounted to slide in a plate *b²* and is adjusted in position by a screw spindle *b³*. The 10 end of the plate *b²* is flanged as at *b⁴* to engage the end of the side of the trough *d*. Roller *c* is similarly mounted in bearing blocks carried by plates such as *c'* but rigid therewith, these plates also having end 15 flanges *c²* serving to anchor them to the side walls. It will be seen that the tensional strain of the endless grate is transmitted through the rollers *b* and *c* and their anchoring plates to the walls of the trough *d*, which is therefore a compression member of 20 the structure.

In the case illustrated the chamber beneath the upper run of the grate is subdivided into three compartments for graduated air supply. The front wall of the chamber is a plate in two parts *o*, *o²*, both carried on a bar *o¹* journalled in the plates *e* and capable of being turned by a handle outside the chamber to lift the lower edge of 30 part *o* from the water in the trough; the upper part *o²* of the plate is stationary and rests against one of the rollers *f*. Plates *p* and *q* mounted similarly to *o* form the partitions between the compartments, each extending to within a short distance of the surface of the water, thus leaving a passage for air from one compartment to the next, which may be increased by turning the bar on which the plate is mounted.

40 The air is in this case delivered by fan *r* to the first compartment through port *s*.

Riddlings that fall through the water on to the lower run of the endless grate may be removed by a scraper *t* placed at a point 45 near the front drum *b* so that the riddlings are removed into a suitable receptacle outside the trough before the grate passes round the drum.

Having thus described the nature of the 50 said invention and the best means I know of carrying the same into practical effect, I claim:—

1. An endless traveling grate stoker comprising an upper run, a stage at the rear of the upper run from which the clinker and ashes are discharged, a lower run and a water trough the surface of the water in which is freely exposed to radiation from the said upper run while a portion of the said lower run travels beneath the surface of the water.

2. An endless travelling grate stoker comprising an upper run, a stage at the rear of the upper run from which the clinker and ashes are discharged, a lower run and a concrete water trough the surface of the water

in which is freely exposed to radiation from the said upper run while a portion of the said lower run travels beneath the surface of the water, end rollers over which the grate travels, and bearings for the said rollers 70 anchored to the ends of the said trough.

3. An endless travelling grate stoker comprising an upper run, a stage at the rear of the upper run from which the clinker and ashes are discharged, a lower run, a water trough the surface of the water in which is freely exposed to radiation from the said upper run, while a portion of the said lower run travels beneath the surface of the water, and side walls enclosing the space between 80 the said upper run and the water surface so as to form an air chamber.

4. An endless travelling grate stoker comprising an upper run and a lower run, combined with a water trough the surface of the water in which is freely exposed to radiation from the said upper run, while a portion of the said lower run travels beneath the surface of the water, and with side walls enclosing the space between the said upper run 90 and the water surface so as to form an air chamber, and a front end wall extending from the said upper run to beneath the water surface.

5. An endless travelling grate stoker comprising an upper run, a stage at the rear of the upper run from which the clinker and ashes are discharged, a water trough beneath the upper run, open-bottomed chambers beneath the said upper run, and means for supplying air to the said chambers.

6. An endless travelling grate stoker having an upper run and a lower run, a water trough beneath the surface of the water in which the said lower run travels, side walls enclosing the space between the said upper run and the water surface, a front wall to the said space extending from the said upper run to beneath the said surface, transverse partitions in the said enclosed space and means for adjusting the distance between the lower edges of these partitions and the water surface.

7. An endless travelling grate stoker having an upper run and a lower run, a front roller and a rear roller over which rollers the travelling grate runs, a concrete or masonry trough beneath the grate, supports for the said rollers anchored to the ends of the said trough, respectively, whereby the trough constitutes a compression member of the construction, the said trough being adapted to contain water the surface of which is freely exposed to radiation from the said upper run while a portion of the said lower run travels beneath the surface of the water.

In testimony whereof I have signed my name to this specification.
